ATTORNEY

UNITED STATES PATENT OFFICE.

CHARLES E. LUCK, OF JAMAICA, NEW YORK.

CUFF-BUTTON.

1,246,124.

Specification of Letters Patent.

Patented Nov. 13, 1917.

Application filed March 25, 1916. Serial No. 86,744.

To all whom it may concern:

Be it known that I, CHARLES E. LUCK, a citizen of the United States, residing at Jamaica, in the county of Queens and State 5 of New York, have invented certain new and useful Improvements in Cuff-Buttons, of which the following is a specification.

This invention has relation to certain new and useful improvements in buttons and relates more specifically to cuff buttons.

An object of the invention resides in the provision of a cuff button which will be constructed of the minimum number of parts and formed in such manner as to be securely held in position and prevented from turning in the cuff.

The invention has for another object the provision of a cuff button which will be constructed in such a manner that when inserted and turned in the cuff, the opposite ends of the movable member will bear against the material to either side of the button hole while the center of the movable member extends into the button hole, thereby securely clamping the button in proper position.

A further object of the invention resides in the provision of a cuff button which will be of extremely simple construction as well 30 as highly efficient in use.

With the above and other objects in view, the invention resides in the novel construction, combination and arrangement of co-operating parts, as will be hereinafter more 35 specifically set forth, pointed out in the appended claims and shown in the accompanying drawings, in which,

Figure 1 is an elevation of the complete device,

Fig. 2 is an elevation at right angles to Fig. 1,

Fig. 3 is an enlarged perspective view, and

Fig. 4 is a detail perspective of the movable member.

Referring more particularly to the drawings in which similar reference characters designate corresponding parts throughout the several views, 1 designates the shank and 2 the head of the stationary member, said 45 shank having a transverse opening 3 in its flattened outer end 4.

The arcuate movable link member 5 is provided in its inner side with an offset central portion 6 which is secured through the 55 opening 3. The arcuate link 5 is preferably secured upon the shank 1 before the

ends of the link are secured together, it being understood that the link 5 is preferably formed of some suitable resilient material such as aluminum. It will be seen that the 60 end of the shank 1 may be readily moved to one end of the link 5 and the button inserted through the button holes, after which the link 5 is moved upon the shank 1 until the central offset portion 6 catches in the opening 3, the ends 7 of the link 5 pressing upon the member through which the shank 1 extends, to either side of the button holes or other openings.

It will be readily seen that a cuff-button 70 formed in this manner will automatically lock itself in the member or members through which the shank 1 is engaged, as the link 5 will automatically adjust itself to proper position with the concaved side of the link 75 toward the material with which the link has a binding engagement. Furthermore it will be evident that the pressure upon the ends 7 of the link will prevent the latter from moving inwardly and thereby disengaging the 80 offset portion 6 from the end of the shank 1 and permitting longitudinal movement of the link through the shank. Therefore the cuff-button will be securely locked in position and casual displacement of the cuff- 85 button will be practically impossible.

It will be noted that in Fig. 4, the shank 1 is shown as being curved and formed with the head 2, while the shank 1 is shown in Figs. 1 and 2 as being straight. It will be 90 understood, however, that the shank 1 may be of any suitable form and the head 2 may be either formed with or mounted upon the shank 1 in any suitable manner. Furthermore the head 2 may be of any desired 95 design.

It will be understood that this button may be used as a lapel button if desired.

While the preferred embodiments of the invention have been shown and described, it 100 will be understood that minor changes in the details of construction, and arrangement of parts may be resorted to within the scope of the appended claims without departing from the spirit of the invention or 105 sacrificing any of the advantages of the same.

What is claimed is:

1. A cuff button comprising a shank, an arcuate link member slidably engaged 110 through and adapted to swing upon said shank, said link member including a concave

2
side and a convex side, a portion of said concave side being offset outwardly for locking engagement with said shank.

5 2. A cuff button comprising a shank, an arcuate link member adjustably mounted on said shank and having an outwardly extended offset portion formed on its concave side to lock said link member in adjusted position upon said shank.

10 3. A cuff button comprising a shank, an arcuate link member slidably engaged through one end of said shank, a head formed upon the opposite end of said shank, said arcuate link including parallel concave and convex side portions, the concave side portion having its center pressed outwardly

to form a locking recess for the first mentioned end of the shank and prevent longitudinal movement of said link through said shank, the ends of the concave side of said link co-operating with the under-face of the head of said button to retain the same in binding engagement with the opposite sides of the member through which the shank is engaged and prevent turning of said button. 20 25

In testimony whereof I affix my signature in presence of two witnesses.

CHARLES E. LUCK.
